UNITED STATES PATENT OFFICE

PATRICK J. KEATING, OF CHICAGO, ILLINOIS.

SOFT-FACE HAMMER.

1,122,506.

Specification of Letters Patent. Patented Dec. 29, 1914.

Application filed July 15, 1912. Serial No. 769,373.

To all whom it may concern:

Be it known that I, PATRICK J. KEATING, a citizen of the United States, residing at Chicago, in the county of Cook and State of Illinois, have invented certain new and useful Improvements in Soft-Face Hammers, of which the following is a specification.

My invention relates to hammers, and more particularly to hammers having a soft end which may be removed and a new one substituted as conditions of usage may render desirable.

It is not broadly new to provide a soft-faced hammer in which a removable head is carried by the hammer body, but various difficulties have been encountered in the manufacture and use of the kinds heretofore suggested. In some cases the head is screwed into the hammer body, in which form it is found that after the head has been used and is battered and the metal of the threaded portion stretched, it is almost impossible to remove the head in order to insert a new one. To avoid this difficulty, it has been suggested that the threads be omitted and a transverse opening be made in the hammer body just below the head or removable plug, and a wedge inserted therein for driving the head out; but in this form the bottom of the plug is not seated against the solid portion of the hammer, the result being that the hammer face becomes concave, and, for another consideration, a firm blow with the full and unyielding force of the hammer cannot be given. Numerous other disadvantages occur in the use of this construction.

It is the object of the present invention to overcome all objections of the kind mentioned, as well as others, and to provide a hammer which shall be simple and cheap in manufacture, which will deliver the full effective power of any hammer of the same size and weight, which shall have a soft head, and one which will remain in the hammer during every kind of service and which shall be easily movable at any stage of wear and which will not, by wedging action of the hammer head itself upon the hammer body, cause the body to expand and be rendered less useful or capable of having another head of standard size substituted as occasion may require or suggest.

In the accompanying drawings forming part of this specification I have illustrated a preferred embodiment of these improvements, the illustration being that of a

double-ended hammer or sledge, although it is evident that the invention may be practised equally well in single-ended hammers of various sizes and shapes, and adapted to many different uses in the mechanic arts.

In these drawings—Figure 1 is a face view of the hammer complete, except for the handle, which is partially broken away; Fig. 2 is a medial cross-section of the hammer body taken at right-angles to the view of Fig. 1, or on the plane of the line 2—2 of Fig. 1. In this view the heads and a punching tool for removing the same are shown in perspective; and Fig. 3 is an end view of the hammer illustrated in Fig. 1.

The hammer body 10 is preferably made of cast steel, and is provided with an eye 11 for the accommodation of the wooden handle 12. As both ends of the hammer illustrated are alike, it will be necessary to describe but one. The end of the hammer body is provided with a recess 13 having the sides substantially vertical to the face 14 of the hammer body, said recess having a bottom 15 substantially parallel with the face 14. Between the bottom 15 and the sides of the recess I prefer to leave a small fillet 17 for purposes of strength. The hammer head is also provided with a slanting aperture or hole 16 leading from the middle portion of the bottom 15 to one of the sides of the hammer body. The plug or head 17 is made preferably of copper, although it may be formed of lead, babbitt, or other of the softer metals, according to the particular use for which it may be desired.

The portion 18 of the head 17 is adapted to fit nicely within the recess 13, this portion being of such length as to seat itself firmly upon the bottom 15. This head also carries an extended portion adapted to seat upon the face 14 of the hammer body. It will thus be seen that the entire projected area of the face of the hammer falls upon the solid hammer body, except for the small area of the hole 16 in the bottom 15 of the plug recess. I have found that the plug or head 17 thus fitting the recess 13 and being seated in the manner indicated, becomes well fixed with usage and does not require any fastening means whatsoever. In fact, after the hammer has been used to a considerable extent, and especially after the exposed portion of the head is battered, it is extremely difficult to remove this plug by any of the usual means at the hands of the

mechanic, such as a vise or chisel. In order to remove these heads quickly and easily, therefore, I provide the hole 16, giving access to the bottom of the plug. By inserting 5 a punching tool, as 20, in the opening 16, and applying hammer blows to the exposed end of the tool, the head is dislodged and forced out of the hammer body. I preferably give the punching tool a slanting face, 10 as shown, so that it will engage the bottom of the head in a way to prevent expanding the metal of the head. The oblique disposition of the passages 16, together with their location equally at opposite sides of the eye 15 11, preserves the balance of the body, while the strength and weight of the body are not materially reduced.

The inclination or slant of the aperture 16 and the slanting face of the punching tool 20 permit this tool in addition to the pressure it exerts on the head 17 to act as a wedge between the bottom 15 of the recess and the adjacent face of the head 17 to force the head out of the recess as blows are struck 25 on the end of the punching tool extending beyond or without the aperture 16.

I have shown the end of the hammer body and the soft head as octagonal in shape, but

it may be circular, of course, and its face may be rounded or given some other suitable 30 character.

It will be apparent to those skilled in the art that various changes and modifications may be made in the details of construction here shown without departing from the 35 spirit or scope of the invention.

I claim:

A hammer comprising a solid body having a central eye and a recess in each end of the body, each recess having a closed bottom, the body being provided with a pair of substantially parallel passages disposed 40 equally at opposite sides of the eye and extending obliquely through the body, the outer ends of the passages opening through 45 respective opposite sides of the body and their inner ends opening into the respective recesses through the bottoms thereof substantially at the middles of said bottoms, and removable heads snugly fitting the recesses and bearing against the bottoms 50 thereof.

PATRICK J. KEATING.
